Primary Examiner — Barbara Fox*Assistant Examiner* — Katie Mroczka(74) *Attorney, Agent, or Firm* — Ladas & Parry LLP(57) **CLAIM**

We claim the ornamental design for a computer monitor, as shown and described.

DESCRIPTION

FIG. 1 is a front/right-side/top perspective view of a computer monitor showing our new design;
FIG. 2 is a front-side elevational view thereof;
FIG. 3 is a rear-side elevational view thereof;
FIG. 4 is a left-side elevational view thereof;
FIG. 5 is a right-side elevational view thereof;
FIG. 6 is a top-side elevational view thereof;
FIG. 7 is a bottom-side elevational view thereof;
FIG. 8 is a back/left-side/top perspective view thereof; and,
FIG. 9 is a cross section view along the line A-A in FIG. 6. Features shown in broken lines are disclaimed and form no part of the claimed design.
